T. B. SCENTER

MINER'S PICK

Filed March 23, 1927

Inventor
Talbert B. Scenter

By *Clarence O'Brien*,
Attorney

UNITED STATES PATENT OFFICE.

TALBERT B. SCENTER, OF CHATTAROY, WEST VIRGINIA.

MINER'S PICK.

Application filed March 23, 1927. Serial No. 177,865.

This invention relates to new and useful improvements in miner's picks, and has for its primary object to provide a pick construction wherein the handle thereof is of hollow metal construction and wherein highly novel, simple, and inexpensive means is provided for rigidly securing the pick head to the handle in such a manner as to prevent the turning of the head upon the handle and prevent the accidental disengagement of the same therefrom.

It is well known that the usual wooden handles of miner's picks are readily breakable due to the striking of the same against the coal especially near the heads thereof, frequently occasioning the loss of an entire day of one of the miners. Also the heads of picks now generally in use are ever liable to become detached from their handles which is an ever present source of danger.

In carrying out the present invention there is provided a hollow metallic handle and a pick head of generally conventional structure, said handle and said head being so formed as to permit of the rigid but yet detachable engagement of the head upon the handle.

With the foregoing and other objects in view as the nature of the invention will be better understood, the same comprises the novel form, combination and arrangement of parts hereinafter more fully described, shown in the accompanying drawing and claimed.

In the drawing:—

The figure is a view mostly in longitudinal section of a miner's pick constructed in accordance with the present invention.

Now having particular reference to the drawing my improved pick consists of a handle 5 of hollow metallic construction of predetermined length and diameter, the inner end thereof being of enlarged cross section as clearly disclosed at 2 in the drawing.

The head 6 is of the double pointed type, and is formed intermediate its ends with a shank 7 similar in cross sectional area and shape to the enlarged end 2 of the handle 5. Formed longitudinally through the shank 7 is a bore 8 threaded throughout substantially its entire length, the inner end of the bore 4 of the handle 5 being also threaded as to facilitate the attachment of the head to the handle by reason of a threaded pin 3 threaded into the head bore and handle bore

as clearly disclosed in the drawing. The head attaching end 2 of the handle 5 at opposed points with respect to the bore 4 is formed with threaded sockets 10—10 that open at the end of the handle. The head 6 is also formed in its shank portion 7 and at opposite sides of the bore 8 with bores 9—9 adapted for registration with the threaded sockets 10—10 in the handle 5 after which elongated bolts 11—11 threaded at their inner ends and headed at their outer ends are arranged through the bores 9—9 and threaded within the sockets 10—10 of the handle 5. As clearly disclosed in the drawing, the heads of the bolts are countersunk within the head of the pick so as to provide a smooth surface at the outer side of the pick head.

It will thus be seen that I have provided a highly novel, simple, and inexpensive miner's pick that is well adapted for all the purposes heretofore designated, and even though I have herein shown and described the invention as consisting of certain detail structural elements it is nevertheless to be understood that some changes may be made therein without affecting the spirit and scope of the appended claim.

Having thus described the invention, what I claim is:—

In a miner's pick of the class described, a tubular metallic handle having its head receiving end internally threaded, a pick head, a shank formed on the inner face of said head for disposition against the inner end of the handle and having a bore extending therethrough in registration with the bore of the handle, said bore being also threaded, a threaded pin arranged within the adjacent ends of the bore of the handle and the bore of the shank for connecting the two together, an additional means for securing the head to the handle, said means comprising a pair of elongated bolts threaded at their inner ends, said pick head and the shank being provided with through bores arranged on opposite sides of the main bore and through which the bolts extend, the inner of the handle being formed with threaded sockets on opposite sides of the bore of the handle for receiving the inner threaded ends of the bolts.

In testimony whereof I affix my signature.

TALBERT B. SCENTER.
